STARTER CONSTRUCTION

Reginald E. Wike, Detroit, Mich.

Application November 7, 1932, Serial No. 641,670

5 Claims. (Cl. 74—7)

This invention relates to a device for use in starting internal combustion engines and the like.

The invention is directed more particularly to a starting device of the above mentioned character which includes a gear or pinion which moves into and out of meshing engagement with another gear by traveling along a screw threaded or similar shaft.

10. The invention has as an object to improve the structure of the traveling gear or pinion to the end that this pinion will mesh readily with the gear to be driven, will quickly move out of meshing engagement with this gear after the engine 15 has been started and will not rebound into contact with the gear to be driven.

Numerous other objects and advantages of this invention will become more apparent as the following description proceeds, particularly when 20 reference is had to the accompanying drawing, wherein:

Fig. 1 is an elevational view showing a starting device constructed in accordance with the teachings of this invention;

25. Fig. 2 is a sectional view taken substantially on the line 2—2 of Fig. 1; and

Fig. 3 is a perspective sectional view of a portion of the structure shown in Fig. 1.

Referring then particularly to the drawing 30 wherein like reference characters designate corresponding parts throughout all views, the numeral 10 designates the flywheel of an internal combustion engine (not shown). This flywheel is provided on its periphery with teeth 11 adapted to be engaged by a driving pinion to impart rotation to the flywheel and to thus start the engine.

The numeral 12 designates the starting motor which may, in accordance with the usual practice, be an electric motor. Mounted on the driven shaft 13 of this motor is a hollow shaft 14 provided with the screw threads 15. The shaft 14 is driven from the shaft 13 preferably by a yieldable connection such as the spring 16 suitably secured to the shafts 13 and 14 in any desired manner.

50. The numeral 20 designates a pinion having internal screw threads 21 which engage the threads 15 on the shaft 14, so that upon relative rotation between shaft 14 and pinion 20, the latter moves longitudinally on the shaft 14. Pinion 20 is adapted to move from its de-meshed position shown in Fig. 1 of the drawing, in which position 55 the end of the pinion abuts the driving head 22

of the shaft 14 to a position where its teeth mesh with the teeth 11 on flywheel 10.

The structure above described is of standard construction and forms no part of the present invention. It is illustrated to disclose one type 5 of starting device in which the present invention about to be described may be incorporated.

It will be understood that in the operation of the above described construction, the parts are normally in the position shown in Fig. 1 of the 10 drawing. When the starter switch (not shown) is closed, the motor 12 is caused to rotate shaft 13 and thus shaft 14. Due to the inertia of the pinion 20, the latter is threaded to the right on shaft 14, and the teeth of the pinion are thus 15 engaged with the teeth on the flywheel. The flywheel is thus driven until the engine starts, at which time the flywheel rapidly rotates the pinion with reference to the shaft 14. This causes the pinion to thread to the left on the shaft, thus returning the pinion to its de-meshed position, shown in Fig. 1 of the drawing.

In a construction of this character the pinion gear should have an eccentric counterweight at the time of closing the starter switch. Such an 25 eccentric counterweight tends to prevent rotation or spinning of the pinion, so that the same will thread to the right on the shaft 14 and thus move into meshing engagement with the teeth on the flywheel.

30. During the cranking operation, however, the eccentric counterweight on the pinion gear should gradually change to a concentric counterweight by the time the motor is ready to start, for the reason that if the counterweight is concentric, the 35 starter pinion will act as a flywheel and thus spin rapidly ahead of the shaft 14 under the impetus given it by the flywheel 10. This rapid spinning of the pinion causes the same to de-mesh quickly.

40. It might be stated that if the counterweight is eccentric at the time the engine starts, there is a tendency for the starter pinion to tilt or become cocked on the shaft 14, thus causing the pinion to bind on this shaft, with the result that the de-meshing of the pinion is retarded. This retardation causes a dragging of the teeth of the pinion on the teeth of the flywheel, resulting not only in a noisy operation, but resulting also frequently in damage to the teeth of the flywheel and 45 pinion gear.

As soon as the pinion gear reaches its full de-meshed position and strikes the stop 22, it is necessary that the energy stored in the rotating 50 pinion gear be dissipated to prevent rebounding 55

of the pinion gear back into engagement with the flywheel. Further, during this dissipation of the energy of the pinion gear, the concentric counterweight of the gear should gradually change to an eccentric counterweight, and the friction causing the dissipation of energy should be proportional to the speed of rotation of the pinion gear. It will be apparent that the changing of the concentric counterweight to an eccentric counterweight prepares the pinion gear for the next starting operation.

The present invention provides a pinion gear having the above discussed characteristics, by associating with this gear a movable weight. This weight is so constructed that it is normally eccentric to the axis of the pinion gear. When, however, the pinion gear is rotated, the movable weight becomes concentric with the axis of the gear. After the starting operation has been completed, the weight functions to dissipate the energy stored in the rotating pinion gear and gradually becomes again eccentric to the axis of the gear, so that the gear is prepared for the next starting operation.

The structure providing a weight capable of acting in this manner is shown more clearly in Figs. 2 and 3. By reference to these figures it will be noted that there is mounted on one end of the pinion gear a housing 25, and this housing provides an annular chamber 26 which extends circumferentially around the axis of the pinion. It will be understood that this housing may be formed in any desired manner and may be secured to the pinion in any convenient way. For the sake of illustration, the housing is shown as having the inner and outer walls 27 and 28, respectively, and the side walls 29 and 30, the latter being secured to the inner and outer walls by bolts or the like 31.

The annular chamber 26 is partially filled with a mobile substance 35, and this substance constitutes the weight. Any number of different substances may be utilized, such, for example, as mercury, sand, small shot, iron filings, or in fact, any substance which will flow sufficiently freely to collect in the bottom of the annular chamber when the pinion is stationary, in the manner illustrated in Fig. 2 of the drawing.

Hingedly mounted in the annular chamber 26 and in spaced relation to each other are a plurality of doors 36, these doors being shown as being hinged as at 37 to the inner wall 27 of the chamber. The doors are in the nature of check valves which open to allow the substance 35 to move in the direction of the arrow in Fig. 2 of the drawing, but which close against the outer wall 28 of the chamber to prevent the reverse or back flow of the substance. It is contemplated that there will be sufficient clearance between the hinges 37 and the inner wall 27 of the chamber to permit any of the substance which is trapped in the upper part of the chamber to flow downwardly to the bottom of the chamber when the pinion is stationary. If sufficient clearance is not obtainable at these points, the doors may be provided with reduced openings 38 through which the substance may flow, as will be readily apparent. If desired, the outer wall 28 of the chamber may be provided at spaced points with inwardly facing shoulders 39, these shoulders being so formed as to be impinged upon by the substance 35 when the latter moves within the chamber 26.

In operation and with the parts in the position shown in Fig. 1 of the drawing, it will be

understood that the substance 35 will be in the bottom half of the chamber 26. Thus this substance will provide an eccentric counterweight for the pinion gear 20. If now, the starter motor 12 is actuated to rotate shaft 14, the pinion 20 will, by virtue of its threaded engagement with the shaft and by virtue of its inertia, move to the right into engagement with the teeth 11 on the flywheel 10. The eccentricity of the counterweight will tend to prevent the pinion from rotating, so that the pinion will readily thread to the right on the shaft and properly mesh with the teeth 11.

After the pinion has become engaged with the teeth 11, continued rotation of the pinion will cause a rotation of flywheel 10 and thus a cranking of the engine. During this cranking operation, the substance 35 will gradually be moved by centrifugal force until it becomes distributed uniformly in the chamber 26, the doors 36 opening readily to permit this even distribution of the weight substance 35. Thus, during the cranking operation, the counterweight will gradually change from its eccentric position to a concentric position. It might be stated that when the pinion meshes with the teeth on the flywheel, the shock of this meshing engagement aids in distributing the substance 35 uniformly within the chamber 26.

As soon as the engine starts, the flywheel 10 will cause the pinion to rotate faster than the shaft 14. By virtue of the fact that the counterweight is at this time concentric with the axis of the pinion, the pinion will act as a flywheel and thus move quickly to the left or to its de-meshed position. Even though a quick rotary impulse is given to the pinion gear at the time that the engine starts, the concentricity of the counterweight is not destroyed for the reason that the doors 36 close and thus prevent the housing from moving ahead of the substance 35. The substance becomes trapped between the several doors and remains evenly distributed within the chamber 26 so that its even distribution about the axis of the pinion gear is not destroyed. As brought out before, it might be stated that during this de-meshing operation it is important that the counterweight be not eccentric to the pinion for the reason that when the counterweight is eccentric, it tends to cause a binding of the pinion on the threaded shaft on which it is mounted, thus retarding to a substantial extent the de-meshing operation.

As soon as the pinion gear hits the stop 22, the moment of inertia of the substance 35 causes this substance to continue its travel within the chamber 26 and about the axis of the pinion gear. This dissipates the energy stored in the rotating pinion gear and prevents the same from rebounding from the stop 22 and into engagement with the flywheel 10. Obviously, at this time the substance gradually returns to its position in the lower half of the chamber 26 and thus becomes again eccentric to the axis of the pinion gear.

It will be apparent that the friction between the substance 35 and the walls of chamber 26 and more particularly the outer wall thereof during the period when the energy in the rotating pinion is dissipated, will be proportional to the speed of rotation of the pinion at the time the latter hits the stop 22. Thus the substance 35 will function to effectively dissipate this energy, regardless of the speed of rotation of the pinion gear at the instant that this gear hits the stop. The shoulders 37 on the inner surface of the outer

wall of the chamber, facing as they do against the direction of movement of the substance 35, act to increase the frictional resistance to movement of the substance 35 within the chamber 26.

5 It is to be understood that whatever material is selected as the substance 35, this material will be sealed within the chamber 26. This may be conveniently effected by soldering or otherwise effectively securing the cover 30 to the inner and 10 outer walls of the chamber. With the material sealed in the chamber in this manner, it will be apparent that there will be no loss of the material by leakage and no reaction of the material to atmospheric changes or the like.

15 It might be stated that if shot, iron filings or the like are utilized as the substance 35, a suitable quantity of lubricating oil might be added to increase the shiftability of this material. If, on the other hand, sand is utilized, the doors 36 20 may, if desired, be eliminated for the reason that the small particles of sand will adhere sufficiently to each other and to the inner surface of the outer wall of the chamber 26 to make the use of the doors 36 unnecessary.

25 It has been stated before that the shoulders 39 are so arranged that they will resist movement of the substance 35 within the chamber 26. It might be stated, however, that these shoulders serve an additional function, namely that of aiding 30 in maintaining the drive pinion adjacent the stop 22.

By reference to Fig. 2, of the drawing, it will be noted that the shoulders are so arranged that those on the right hand side of the axis of the 35 pinion gear, as viewed in Fig. 2, face upwardly. When the pinion gear is in its de-meshed position, the constant motor vibration tends to cause the substance 35, particularly if this substance 40 be sand, to pile up on the shoulder or shoulders at the right hand side of the axis of the pinion gear, thus slightly adding to the weight on this side of the axis. This slight additional weight prevents the pinion gear from moving or creeping 45 away from the stop when subjected to continuous vibration, tending rather to cause the pinion gear to creep in a direction which will move it toward the stop 22.

From the above it will be apparent that the invention provides a counterweight adapted to be 50 associated with the pinion gear of a starter construction and capable of changing from a position eccentric to the axis of the pinion gear to a position concentric with reference to said axis. Further, the movement or shifting of the counterweight will be entirely automatic, with the 55 result that the pinion gear will at all times be properly counterweighted to effect the desired results.

While the invention has been described as being 60 incorporated in the pinion gear of an engine starter construction, it is to be understood that the inventive principles disclosed may be incorporated in other constructions wherein it is desired to have a counterweight capable 65 of shifting in the manner described. Still further, while the mobile substance which constitutes the counterweight has been shown as being

housed in a chamber located at one end of the pinion gear, it will be apparent that, if desired, this chamber might extend the length of the pinion gear, the teeth on the pinion gear being formed in this case on the outer surface of the outer wall 28 of the chamber. These and numerous other changes may be made in the details of construction and arrangement of parts, so that it is to be understood that this description is for the purposes of illustration only and is not 10 definitive of the limits of the inventive idea, the right being reserved to make such changes as will fall within the purview of the attached claims.

What I claim as my invention is:

1. In a starter construction, the combination with a threaded shaft, a threaded pinion thereon, and a gear to be started by the pinion, of means carried by said pinion providing a sealed annular chamber surrounding the axis of rotation of the pinion, and a quantity of a mobile substance in said chamber and constituting a weight for said pinion.

2. In a starter construction, the combination with a starter pinion, of means carried by said pinion and providing an annular chamber surrounding the axis of rotation of the pinion, a quantity of a mobile substance in said chamber and partly filling the same, and baffles hingedly mounted at spaced points in said chamber 30 for restraining the said mobile substance against movement in one direction in said chamber.

3. In a drive for an engine starter, the combination of a rotatable screw member, a member screw-threaded thereon and capable of longitudinal movement thereof and rotary movement therewith, means providing an annular chamber surrounding said member, a quantity of a mobile substance in said chamber and partly filling the same, baffles hingedly mounted at 40 spaced points in said chamber, and means providing shoulders projecting interiorly of said chamber from the outer wall thereof.

4. In a starter construction, the combination with a rotatable threaded shaft, a pinion threaded on said shaft for axial movement relative thereto, and a gear adapted to mesh with said pinion upon a predetermined axial movement of the latter providing for rotation of the pinion by the shaft, of a mobile substance constituting a weight for said pinion and normally disposed at one side of the axis of the pinion to assist movement of the latter axially of said shaft.

5. In a starter construction, the combination with a rotatable threaded shaft, a pinion threaded on said shaft for axial movement relative thereto, and a gear adapted to mesh with said pinion upon a predetermined axial movement of the latter providing for rotation of the pinion by the shaft, of a mobile substance constituting an eccentric weight for said pinion when the latter is out of mesh with said gear and responsive to the rotation of the pinion to become 60 evenly distributed around the axis of the latter.

REGINALD E. WIKE.
